(57) **CLAIM**

I claim, the ornamental design for a paneled hypar canopy, as shown and described.

DESCRIPTION

FIG. 1 is a perspective view of a paneled hypar canopy showing my new design;

FIG. 2 is a front elevation view, the rear being a mirror image thereof;

FIG. 3 is a right side elevation view, the left side being a mirror image thereof;

FIG. 4 is a top plan view thereof, the bottom being a mirror image thereof; and,

FIG. 5 is a perspective view of a second embodiment of a paneled hypar canopy showing my new design.
